UNITED STATES PATENT OFFICE.

WILLIAM H. NICHOLS, OF WILKINSBURG, PENNSYLVANIA.

APPARATUS FOR CASTING CHILL ROLLS AND THE LIKE.

Application filed December 17, 1928. Serial No. 326,586.

My invention is an improvement in the art of chill roll castings or the like. It has in view to provide an improved means for simplifying and improving the manufacture and the product of chill castings of any kind capable of being made, following my invention, and especially in the art of making chilled rolls.

Ordinarily, in the manufacture of chill rolls or other cylindrical bodies, the face of the roll is cast against a solid metal ring of steel or iron of sufficient sectional depth to ensure quick extraction of the heat of the metal being formed.

In the common practice of casting chill rolls it is difficult to control the uniform depth of the chill evenly all around, with uniformity of diameter. Also to avoid fire cracking of the solid chill, while the formation of pin holes and other defects due to confined gases, tends to imperfection of surface.

In my improvement, I provide a sectional chill composed of a series of annular wall members within an outer confining case or flask, with ventilation spaces, bearing portions, and other features.

The invention provides for the placement or location at any desired position, of an annular series of segmental sections, with ample facility for escape of hot gases or air and rapid heat extraction from the casting.

The invention is adaptable to plane cylindrical surfaces, or to angular depressions at any portion of the mold cavity, for local chilling at any portion or portions, as hereinafter described.

In the drawings showing one preferred embodiment of the invention adapted to utilize the invention:

Fig. 1 is a plan view of a chill mold for casting chill rolls according to my invention;

Fig. 2 is a vertical section on the line II—II of Fig. 1;

Fig. 3 is a perspective detail view of one of the filler blocks or sections, detached;

Fig. 4 is a partial sectional view, like Fig. 2, showing application of the invention to corner recesses of the mold, for local chilling;

Fig. 5 is a partial cross section on the line V—V of Fig. 4;

Fig. 6 is a view like Fig. 3, showing one of the segments detached as used in corner chilling;

Fig. 7 is a partial sectional view showing the application of the invention for applica-

tion of a chill to the groove portion of the body of a roll.

In the drawings, 2 is the outer flask or casting surrounding the main middle casting cavity of the roll or other article to be made. It is adapted to interfit and connect above and below with any suitable supplemental neck molding flask extensions, for ordinary sand molding of the roll necks, or for additional chill molding sections, as desired.

The flask 2 is of any suitable construction, but for roll casting it is cylindrical, having an interior smooth annular surface 3, preferably turned for true engagement with the abutting ends of the several inner sections *a*.

The annular wall 2 of the flask is provided with a plurality of gas release ports 4 suitably arranged as shown, and the lower inner wall is preferably provided with an inwardly extending annular shoulder 5 for supporting the sections in place.

Sections *a* are of segmental shape, for the full or part depth only of the main vertical casting cavity, as when two or more vertical series are employed, with the remaining wall of sand.

Each segmental section *a* is provided with radially arranged meeting faces 6, 7, at its inner and outer portions for making contact with similar faces of adjacent sections all around the entire annular series.

The inner meeting faces 6 are continuous from top to bottom, thereby forming a substantially continuous inner cylindrical surface when assembled, while the rear faces 7 are interrupted by alternating channels 8. These communicate with main channels or depressions 9 extending from top to bottom, between the continuous extended inner meeting faces 6 and the alternating or separated outer faces 7. The outer or wider end of each section *a* is also preferably provided with a vertical groove or gutter 10 from top to bottom as shown, the several grooves and depressed portions throughout the series operating to provide numerous channels for escape of gases generated by the hot metal as poured.

Such gases have free access to the outside of the mold either through the ports 4 or upwardly and downwardly endwise of the flask.

When the annular series of sections *a* is properly fitted it forms a continuous ring with a succession of closed vertical joints, but

continuously smooth. When two or more series are utilized, the joints may be off-set or broken as in Fig. 2, but in either case there is ample and frequent opportunity for gas 5 leakage throughout.

The chill sections as thus arranged are sufficiently flexible as a whole under the changing heat conditions to provide for any possible expansion and contraction without 10 danger of fracture, while ensuring symmetry and regularity of body texture of the casting.

Obviously the segmental sections *a* first become heated to a higher temperature than the surrounding shell 2, and will expand inwardly towards the roll center, being retained by the cooler outer shell, which becomes heated later. In this manner the roll 15 surface is closely confined and the edge joints of the segments are tightly closed.

20 The extracted heat of the metal is first absorbed by the inner portions of the segments, and then by the casing, the speed of extraction being increased by the numerous gas and air channels and ports in both.

25 Due to the ventilation of the chill portion of the mold as a whole, pin holes or other defects due to contained gas are avoided, resulting in greater uniformity of surface regularity. The uniformity of body diameter 30 and of depth of chill, is also more evenly maintained.

The outer flask being a permanent portion of the equipment, any one or more of the sections *a* may be replaced if worn or broken, 35 at a minimum of cost. Due to the free radiation of heat, I have found that a large percentage of fire cracking common in the old form of solid chill flasks is obviated. The operation of casting chill rolls or the like is 40 not only greatly improved both in method and product, with a shortening in time, but the cost of manufacture is materially reduced.

The side contacting faces 6, 7, being on 45 common planes provide for easy planing and finishing, the several faces projecting beyond the recessed circulation clearance spaces in the manner of chipping strips.

When it is desired to chill only certain 50 portions or zones of the roll being cast, as the grooves or passes of shaping rolls, the segments may be formed with inner conforming chill sections adapted to surround the portion to be controlled.

55 Thus in Fig. 4 I show one side of a roll mold for casting a roll in which a rail groove *b* is to be turned. In such case the segment *a'* is off-set as at 11, providing the inner projecting portion 12 partly or entirely forming the chill surface for the necessary area 60 of the roll in which the groove is to be turned.

In such form of segment the circulation depression 9 extends inwardly by an angular pocket 13 towards the neck of the roll, the 65 shouldered form of the segments presenting

greatly increased contacting surfaces for rapid heat extraction.

Fig. 4 also illustrates the manner in which portions of the mold may be made up of annular sections of ordinary molding sand 14 70 between spaced apart chill sections and within continuous sections of shells. Such arrangement may be utilized when a portion or portions of the roll are of ordinary sand casting, without chill, as for the molding of a 75 roughing roll groove, etc.

On the other hand any intermediate portion of the roll may be chilled between ordinary sand cast sections, by the use of an intermediate series of segments *a''* as in Fig. 7. 80

The segments in such case are generally the same as above described, and may be deflected inwardly for chill groove formation as at 15, the side channels being also deflected inwardly as at 13.

What I claim is:

1. A chill roll casting mold comprising an outer cylindrical metal shell provided with ventilating ports and an annular series of segmental chill sections therein having inner 90 contacting faces and sides with intervening clearance depressions in the sides providing circulation spaces.

2. A chill roll casting mold comprising an outer cylindrical metal shell provided with 95 ventilating ports and an annular series of segmental chill sections therein having inner contacting faces and sides with intervening clearance depressions in the sides providing 100 circulation spaces and communicating depressions leading to the outer shell.

3. A chill roll casting mold comprising an outer cylindrical metal shell provided with ventilating ports and an annular series of segmental chill sections therein having inner 105 contacting faces and sides with intervening clearance depressions in the sides providing circulation spaces and having circulation channels along their outer shell engaging edges.

4. In combination, an outer annular metal shell having series of circulation ports therethrough and an inner series of segmental chill sections in close contacting engagement with each other along their inner side 115 edges and having outer similar contacting side edge abutments interrupted by circulation channels.

5. In combination, an outer annular metal shell having series of circulation ports there- 120 through and an inner series of segmental chill sections in close contacting engagement with each other along their inner side edges and having outer similar contacting side edge abutments interrupted by circulation 125 channels, the intervening faces between the inner and outer side edges being depressed to provide circulation channels communicating therewith.

6. In combination, an outer annular metal 130

shell having series of circulation ports there-through and an inner annular shoulder, and an inner series of segmental chill sections in close contacting engagement with each other 5 along their inner side edges and provided with circulation depressions, and having an annular off-set shoulder engaging the inner shoulder of the shell.

7. A segmental shaped metal chill section 10 for a chill roll mold having a continuous contact face along each inner side, a depressed middle side face, and contact faces along its outer side faces interrupted by circulation channels communicating with the side face 15 depressions.

8. A segmental shaped metal chill section 20 for a chill roll mold having a continuous contact face along each inner side, a depressed middle side face, and contact faces along its outer side faces interrupted by circulation channels communicating with the side face depressions, and provided with a vertical circulation channel along its rear shell contacting 25 face.

9. A segmental shaped metal chill section 25 for a chill roll mold having an inwardly deflected angular molding face and a correspondingly deflected continuous contact face along each inner side, a depressed middle side 30 face inwardly deflected between said contact faces, and contact faces along its outer side

faces interrupted by circulation channels communicating with the side face depressions.

10. A segmental shaped metal chill section 35 for a chill roll mold having an inwardly deflected angular molding face and a correspondingly deflected continuous contact face along each inner side, a depressed middle side face inwardly deflected between said contact 40 faces, and contact faces along its outer side faces interrupted by circulation channels communicating with the side face depressions, and provided with a vertical circulation channel along its rear shell contacting 45 face.

11. A segmental shaped metal chill section 50 for a chill roll mold having an inwardly deflected angular molding face and a correspondingly deflected continuous contact face along each inner side, a depressed middle 55 side face inwardly deflected between said contact faces, and contact faces along its outer side faces interrupted by circulation channels communicating with the side face depressions, and provided with a vertical circulation channel along its rear shell contacting face and an off-set supporting shoulder.

In testimony whereof I hereunto affix my signature.

WILLIAM H. NICHOLS.
